US00D850558S

(12) **United States Design Patent** (10) **Patent No.:** **US D850,558 S**
Fournet (45) **Date of Patent:** **** Jun. 4, 2019**

(54) **GUN COCKING DEVICE**

(71) Applicant: **George J. Fournet**, Youngsville, LA (US)

(72) Inventor: **George J. Fournet**, Youngsville, LA (US)

(**) Term: **15 Years**

(21) Appl. No.: **29/599,211**

(22) Filed: **Mar. 31, 2017**

(51) LOC (11) Cl. **22-01**

(52) U.S. Cl.

USPC **D22/108**

(58) **Field of Classification Search**

USPC D22/100, 108, 109, 110, 199; D12/114, D12/223, 162, 349; 42/111, 114, 94; D6/552; 102/430; 114/218; 224/192, 224/193, 243, 912, 198, 199, 238, 239, 224/244, 911, 311, 442, 413, 571, 551, 224/521; 89/1.4, 40.01, 40.03, 37.04; 211/66, 64; D8/363, 381, 349, 373, 380, D8/354, 356, 396; 248/309.1, 309.2, 317, 248/274.1, 284.1, 300, 27.1, 200; 280/415.1, 416.1, 507-511, 491.1-491.3; 15/314

(57) **CLAIM**

The ornament design for a gun cocking device, as shown and described.

DESCRIPTION

FIG. 1 is a perspective view of one embodiment of the gun cocking device showing my new design.

FIG. 2 is a perspective view of one embodiment of the gun cocking device showing my new design.

FIG. 3 is a top view of one embodiment of the gun cocking device showing my new design.

FIG. 4 is a bottom view of one embodiment of the gun cocking device showing my new design.

FIG. 5 is a front view of one embodiment of the gun cocking device showing my new design.

FIG. 6 is a rear view of one embodiment of the gun cocking device showing my new design.

FIG. 7 is a side view of one embodiment of the gun cocking device showing my new design; and,

FIG. 8 is an opposite side view of one embodiment of the gun cocking device showing my new design.

The broken lines in the drawings are used to illustrate unclaimed portions and environment, and form no part of the claimed design.

1 Claim, 4 Drawing Sheets
